Fig. 1.

Fig. 2.

Fig. 3.

Fig. 4.

FIG. 1 is a side elevational view of a tumbler or a similar article showing my new design;

FIG. 2 is a top view thereof;

FIG. 3 is a bottom view thereof;

FIG. 4 is a developed plan view thereof, the background surface texture having been omitted for convenience of illustration;

FIG. 5 is a side elevational view of a tumbler showing my new design in the size and proportions of an old fashioned glass;

FIG. 6 is a side elevational view of a tumbler showing my new design in the size and proportions of an iced tea glass;

FIG. 7 is a side elevational view of a tumbler showing my new design in the size and proportions of a collins glass; and

FIG. 8 is a side elevational view of a tumbler showing my new design in the size and proportions of a juice glass.

The background surface ornamentation of the sides of the tumbler which is not visible in FIGS. 1, 5, 6, 7 and 8 is substantially similar to that shown on the side of the tumbler in FIGS. 1, 5, 6, 7 and 8.

I claim:

The ornamental design for a tumbler or similar article, substantially as shown and described.
